GRASS KILLING APPLICATOR FOR EDGING LAWNS

Robert S. Wise, Wichita, Kans., assignor to Robert S. Wise Company, Inc., Wichita, Kans., a corporation of Kansas

Filed Feb. 27, 1962, Ser. No. 69,000

Term of patent 14 years

(Cl. D35—2)

Fig. 1.

Fig. 2.

Fig. 3.

Fig. 4.

FIG. 1 is a perspective view of a grass killing applicator for edging lawns showing my new design;

FIGS. 2 and 3, respectively, show the side and end opposite those shown in FIG. 1.

FIG. 4 is a top plan view of the same.

I claim:

The ornamental design for a grass killing applicator for edging lawns, as shown and described.
